UNITED STATES PATENT OFFICE.

MARY E. CROWELL AND LA VAUGHN CROWELL, OF CULBERTSON, NEBRASKA.

KNITTING-NEEDLE HOLDER.

1,372,648.

Specification of Letters Patent. Patented Mar. 22, 1921.

Application filed April 15, 1918. Serial No. 223,634.

To all whom it may concern:

Be it known that we, MARY E. CROWELL and LA VAUGHN CROWELL, citizens of the United States, residing at Culbertson, in 5 the county of Hitchcock and State of Nebraska, have invented certain new and useful Improvements in Knitting-Needle Holders, of which the following is a specification.

This invention relates to new and useful 10 improvements in holders and more particularly to a device adapted to securely engage the opposite ends of a plurality or a single knitting needle, so as to afford a means for securely holding the same with the points 15 thereof protected likewise forming means for connecting a set of knitting needles and preventing certain of the needles from being misplaced.

Another object of the invention is to provide 20 a device of this character which is easily and simply constructed, inexpensive to manufacture and one which will be very efficient in operation.

With these and numerous other objects in 25 view, our invention consists of the novel features of construction, combination and arrangement of parts which will be herein referred to and more particularly pointed out in the specification and claims.

30 In the accompanying drawings:

Figure 1 is a side elevation of the device, with the needles shown in dotted lines positioned therein,

Fig. 2 is an end elevation of one of the 35 holders showing a cross section of the spring, and

Fig. 3 is a longitudinal section through one of the cap holders.

In describing our invention, we shall refer 40 to the drawings in which similar reference characters designate corresponding parts throughout the several views.

The numerals 1 and 2 designate a pair of 45 holding caps which are adapted to be positioned over the opposite ends of the knitting needles 3 as shown in dotted lines in Fig. 1 of the drawings, said caps being formed of any desired material, being of any design, and arranged so that the open ends thereof 50 are oppositely disposed.

The caps 1 and 2 are adapted to be connected by a coil spring 4 which has its op-

posite ends secured to the outer side wall of each cap by a fastening member 5 positioned therethrough, as is clearly shown in Fig. 3 55 of the drawings. This coil spring is of the expansion type and is shorter than the conventional size of knitting needle so that the spring will have to be expanded so as to position the ends of the needles in the caps carried by the opposite ends of said spring. 60

In operation, when it is desired to secure a set of knitting needles within the holding caps the spring is expanded and the needles positioned therein, as is clearly shown in 65 Fig. 1 of the drawings. The contraction of the spring 4 will draw the caps tight against the opposite ends of the needles, and hence said needles will be securely positioned between the caps, and will form a compact 70 package that may be carried in a minimum amount of space. The holding caps, by connecting the needles together, likewise prevent said needles from becoming lost or misplaced.

This type of needle holding device is very 75 simple in construction, but the advantages derived therefrom are numerous. It forms a very efficient holder for securing a set of knitting needles when not in use, and likewise affords a protection against the sharpened points of the needles. Although the device is especially adapted for application on knitting needles, it is obvious that the same may be applied for various other purposes. The spring 4 may be adjusted to correspond approximately to the different 80 lengths of needles upon which the holder is to be used.

From the foregoing description taken in 90 connection with the accompanying drawings, it is thought that a clear and comprehensive understanding of the construction, operation and advantages of our invention may be had, and while we have shown and described the 95 device as embodying a specific structure, we desire that it be understood that such changes may be made in said structure as do not depart from the spirit and scope of the invention as claimed.

Having fully described our invention, what we claim as new, and desire to secure by Letters Patent, is:

A knitting needle holder comprising hol-

low caps for disposition over the opposite ends of one or a plurality of knitting needles, a flexible connection only between said caps in the form of a contractile coiled 5 spring of less normal length than the needles to be mounted in the holder, the terminals of the contractile spring being bent to form

eyes, and means extending through the eyes for securing the spring to the caps to hold the same upon the needle ends. 10

In testimony whereof, we affix our signatures hereto.

MARY E. CROWELL.
LA VAUGHN CROWELL.
